UNITED STATES PATENT OFFICE.

JOHN L. BLOCKBURGER, OF CHICAGO, ILLINOIS.

AUTOMATIC MOTOR-STOPPING DEVICE.

1,079,324.

Specification of Letters Patent. Patented Nov. 25, 1913.

Application filed September 12, 1912. Serial No. 719,932.

To all whom it may concern:

Be it known that I, JOHN L. BLOCKBURGER, a citizen of the United States, residing at Chicago, in the county of Cook and State of Illinois, have invented certain new and useful Improvements in Automatic Motor-Stopping Devices, of which the following is a specification.

My invention relates to improvements in automatic motor-stopping devices and more particularly to a device for automatically stopping the motion of talking machines, upon completion of a record.

One of the objects of my invention is to provide an efficient means, operable with a minimum of effort on the part of the user, adapted for adjustment to control the moment of operation of the device to correspond exactly with the end of the particular record.

To this end, a more particular object of my invention is to provide, in conjunction with the above mentioned adjustment means, means whereby the adjustment may be made even before the particular record is placed upon the record-receiving table of the talking machine, such means taking the form of an indicator having indicia corresponding to indicia which may have been placed previously upon the particular record.

Further my invention contemplates an arrangement of particular parts peculiarly adaptable for use to accomplish the above results, without change in the talking machines to which it is applied, my device being cheap and simple of construction, easy to apply, and not accompanied with such disadvantages as adding unnecessary weight to the needle carrying frame of the talking machine, providing parts bearing upon the record, or extending over the record, or intended to interfere with the needle, either during operation or at the close thereof, and not imposing upon the usual motor of the talking machine any burden such as ratchet-and-pawl counting devices, which, besides involving considerations of the number of threads on the record, require power during the playing of the record.

Other and further objects of my invention will become apparent from a consideration of the following description when taken in conjunction with the drawings, wherein—

Figure 1 is a plan view of a talking machine of the disk type with an automatic stopping device applied thereto in accord-

ance with my invention; showing the electromagnet energized and the brake of the talking machine on; Fig. 2 is a section through the casing of the talking machine, 60 showing some of the parts in side elevation; Fig. 3 is an enlarged elevation, partly in section, of the brake and appurtenant parts; and Fig. 4 is an enlarged plan view with parts broken away, of the brake and the operating electromagnet therefor. 65

In the drawings I have shown my invention applied to a conventional talking machine of the type where the records are disk shape, and it will of course be understood 70 that the invention is also applicable to other types of talking machines.

In the construction shown, 5 indicates the casing of the talking machine, 6 the rotating table to receive the record (shown at 6' in Fig. 1), 7 indicates the reproducer or sound-box of ordinary construction carrying the needle 8 and carried by the hollow arm 9 which is pivotally mounted, as at 10, for sound-transmitting communication with the 75 horn or other enlarged outlet from which the sound issues, the pivotal mounting of the arm 9 permitting free swinging movement thereof as when the needle 8 follows the threaded track on the rotating record. 80 85

My invention may be conveniently embodied by the use of batteries and an electromagnet with a suitable circuit for the electromagnet, to be automatically made as soon as the needle 8 reaches the end of the 90 track on the record 6'. This making of the circuit may be readily attained by mounting upon the casing of the talking machine a contact for coaction with the arm 9 to complete the circuit for the electromagnet. 95

Specifically, 12 indicates the batteries, herein shown as dry batteries; 13 indicates the electromagnet arranged within the casing suitably positioned with respect to a brake device, to be described, and 14 indicates the contact for coöperation with the arm 9, said contact herein taking the form of a post having its pointed free end bent over, as at 15, toward the arm 9, said post 14 being preferably mounted for rotation with some frictional resistance so that the position of the bent over portion 15 with respect to the arm 9 may be adjusted to vary the moment of contact. Thus, a record being placed upon the table 6 and arm 9 placed so that the needle 8 stands at 100 105 the end of the record-thread, post 14 may

110

be swung to contacting position where it will remain to receive contact from arm 9 at the proper moment after operation of the talking machine. For further advantage in 5 setting the device for the particular record, I provide an indicating means herein shown, for convenience and simplicity, as the segmental gear member 14^a secured on post 14 and meshing with pinion 14^b. The pinion 10 14^b carries pointer 14^c for coaction with a scale 14^d. Therefore, when the post is set as above described by means of the arm 9, note of the scale reading may be made on the particular record so that all subsequent 15 settings for that record involve only the movement of post 14 to bring pointer 14^c to the scale line noted on the record.

The brake device, usually provided upon 20 talking machines of this type, includes a spring-pressed plunger 17, the spring 18 whereof engages between a shoulder 19 and the end of a plunger casing 20. The plunger 17 is provided with a pin 21 extending downwardly therefrom through a slot 22 in 25 the casing 20. The casing 20 is provided with laterally extending lugs 23 for attachment as by screws 24 to the casing, and pivoted as at 25 is an operating lever 26 having a cam-portion 27 for coaction with the pin 30 21 of the brake plunger. Thus, said plunger may be moved out of engagement with the table 6 or the compression spring 18 may be permitted to push the plunger into frictional engagement therewith, accordingly as 35 the lever 26 is in the position shown in Fig. 4 or Fig. 1 respectively. It will be noted that as soon as lever 26 is moved part way from its record-releasing position, shown in Fig. 4, the coaction of pin 21 upon the cam 40 surface 27 causes the lever 26 to move to its final position shown in Fig. 1 without further manual operation, since the spring 18 pushes the pin 21 against the cam 27. Therefore, lever 26 will always automatically move 45 to its final position shown in Fig. 1, even if not moved quite so far by manual means or the automatic means hereafter described.

Utilizing this construction to accomplish the desired ends, I may employ the lever 26 50 as one of the contacts of an electric circuit including the electromagnet 13, the coacting contact being a member controlled by the electromagnet for moving the lever 26 from its releasing position (Fig. 4) to stopping position (Fig. 1). Specifically, the casing 55 may be bored, as at 28, and preferably also provided with a plate 29 surrounding the bore and secured to the casing additionally to the screws 24, by screws 30.

60 The operating means for the lever 26 controlled by the electromagnet 13 is herein shown as a bell-crank lever 31, one arm 32 of which constitutes the armature for the electromagnet 13 and the other arm 33 of 65 which extends upwardly as at 34 for coac-

tion with the lever 26. It will be noted that lever 26 and the vertical portion 34 of arm 33 are in contact when the parts are in the position shown in Fig. 4,—the brake being off—and that in such position the armature 70 32 of the electromagnet is retracted.

The electrical circuits for the devices above described may be as follows: From the battery 12, wire 35 extends into connection, as by binding post 36, with the pivoted metallic 75 arm 9 of the talking machine mechanism, and wire 37 extends from the post 14 (binding post 38) into connection, as at 39, with the brake mechanism above described, the lever 26 constituting a contact for coaction 80 with the vertical portion 34 of the armature-controlled lever 33, which is connected as by wire 40 to the electromagnet 13 and thence by wire 41 to the other terminal of the battery 12. It will thus be seen that there is provided for the battery a circuit which is closed 85 only when the pivoted arm 9 and the post 14 are in contact and at the same time lever 26 and the armature-controlled portion 34 are in contact.

Before starting, the post 14 is adjusted as 90 above described. Then, during operation, the arm 9 gradually moves nearer and nearer to the adjusted post 14 until contact between the arm 9 and the post 14 is finally made at 95 the moment the record is finished. Therefore, parts 34 and 26 being in contact, the circuit is completed as follows: 12, 35, 36, 9, 15, 14, 38, 37, 39, through the plate 29 to the lever 26, 34, 33, 31, 40, 13, 41, 12, so 100 energizing the electromagnet 13 which retracts its armature 32 so moving lever 26 from the position shown in Fig. 4 to the position shown in Fig. 1. This movement of the lever 26 operates as above described to 105 stop rotation of the table 6 by permitting spring-impelled movement of the plunger 17 thereagainst.

It will be remembered that the lever 26 having been positively moved a part of the 110 way toward locking position, automatically completes its movement to position shown in Fig. 1 independently of the initiating means (armature-controlled part 34). I therefore 115 preferably arrange the parts in such manner that the armature 32 when fully attracted as in Fig. 1 will not have brought the member 34 far enough in the direction of lever 26 to be in contact therewith, so that the circuit is automatically broken the moment the lever 26, under influence of spring 18 moves farther than the armature 32 will permit the portion 34 to move, the circuit being therefore 120 broken the moment the record-receiving table 6 has been stopped. It will thus be apparent that when the device is started in 125 operation, the user may leave the instrument without need of returning until a new record is to be played, when the operation as above described is simply repeated, lever 26 130

of course being manually returned from locking position shown in Fig. 1 to the releasing position shown in Fig. 4 to permit rotation of the table 6.

5 While I have herein described an embodiment of my invention it will be apparent that many changes may be made in the parts employed in the carrying out of my teachings and in adapting the device to existing 10 types of talking machines, and it will be apparent to those skilled in the art that my invention is therefore not limited to the single embodiment shown for purposes of full disclosure further than is specifically indicated by the appended claims.

What I claim is:

1. A brake mechanism of the character described comprising in combination a traveling element, a brake plunger, an electric circuit, means included in the circuit for controlling the brake plunger, one terminal of the circuit being adapted for electric connection with the traveling element, a contact for the other terminal of the circuit, said contact comprising a rotatably adjustable post having a crank arm adapted to be set in the path of said traveling element, a scale, a pointer in coöperative relation with the scale, and means for moving the pointer over the scale by rotation of the post.

2. The combination of a casing having a top, a rotatable element mounted on the upper side of the top, a swinging arm pivotally supported above the top of the casing and working across the rotatable element, a brake plunger mounted on the casing top in coöperative relation with the rotatable element, an electric circuit disposed beneath the

casing top with one terminal connected with the swinging arm, means included in the circuit and located below the casing top for controlling the brake plunger, a contact comprising a rotatable post connected with the other terminal of the electric circuit and rising above the casing top and provided with a crank arm disposed in the path of the swinging arm, a scale on the casing top, a pointer pivoted upon the casing top in coöperative relation with the scale, a pinion for the pivot of the pointer, and a gear in mesh with the pinion and carried concentrically by the post.

3. The combination of a rotatable member, an arm mounted to travel with respect to the rotatable member, a brake plunger mounted to contact said member, electrically operated releasing means for said plunger including an adjustable contact adapted to be positioned in the path of movement of said arm, a scale graduated with respect to predetermined operative positions of said arm, a pointer mounted for movement in proximity to said scale, and an operative connection between the pointer and the contact whereby a desired position of the contact in the path of movement of said arm is secured upon adjustment of the pointer to a predetermined position indicated by said scale.

In testimony whereof I hereunto set my hand in the presence of two witnesses.

JOHN L. BLOCKBURGER.
